COMBINED TRANSFORMER AND ILLUMINATING DEVICE

James A. Comstock, Cleveland, Ohio, assignor to
The Acme Electric & Manufacturing Company, Cleveland, Ohio, a corporation of Ohio

Application January 15, 1936, Serial No. 59,251

9 Claims. (Cl. 240—11.4)

My invention relates generally to a combined transformer and illuminating device.

An object of my invention is the provision of constructing a transformer and an illuminating device as a unit which may be suspended by any suitable means such, for example, as by the conduit through which the supply conductors pass upon entering the transformer housing.

Another object of my invention is the provision of a transformer housing having the two end portions, one of said end portions being adapted to carry the illuminating device and the other end portion being adapted to provide space for making electrical connections with the supply circuit.

It is a further object of my invention to provide for suspending the combined transformer and illuminating device as a unit.

A further object of my invention is the provision of a transformer housing having two end brackets, one of said brackets being adapted to carry the weight of the illuminating device and the other bracket being adapted to engage the conduit from which it may be suspended and carry the combined weight of the transformer and the illuminating device.

A still further object of my invention is the provision of mounting an electrical socket for an illuminating device upon a transformer housing so that the combined socket and transformer housing may be suspended as a unit.

It is also an object of my invention to provide for mounting a transformer and a capacitor in a housing and for suspending an electrical socket for receiving an illuminating device upon the housing and suspending the entire unit as a combination.

A still further object of my invention is to provide for mounting an electrical socket for receiving an illuminating device in the end portion of a housing that encloses a transformer which energizes the illuminating device.

It is also an object of my invention to construct an illuminating device with both incandescent lamps and with gaseous tube lamps and to suspend said illuminating device by a transformer housing having a high leakage reactance transformer for energizing the gaseous tube lamp and having supply conductors for energizing the incandescent lamp.

Other objects and a fuller understanding of my invention may be had by referring to the following description and claims, taken in combination with the accompanying drawings in which:

Figure 1 illustrates a combined transformer

and an illuminating device embodying the features of my invention;

Figure 2 is an enlarged and a cross-sectional view of the combined transformer and the illuminating device shown in Figure 1;

Figure 3 is a modified form of my invention and illustrates in addition to the embodiment shown in Figures 1 and 2, a capacitor mounting in the transformer housing to improve the power factor of the lighting circuit;

Figure 4 is another form of my invention and shows the socket for the lighting device mounted in the end lower portion of the transformer housing;

Figure 5 is another form of my invention wherein the illuminating device is suspended at a distance below the transformer housing by a conduit and wherein the electrical connections for the supply conductors are made in a conduit box above the transformer housing; and

Figure 6 illustrates a diagrammatic view of a reactance coil for controlling the energization of the illuminating device instead of the high leakage reactance transformer shown in the other forms of my invention.

With reference to Figures 1 and 2, my invention comprises two main parts, (one) an electrical energizing device indicated generally by the reference character 10, and (two) an illuminating device indicated generally by the reference character 11.

The electrical energizing device 10 will be described first. As illustrated in Figure 2, the electrical energizing device 10 comprises briefly a transformer 12, a housing 18 for the transformer, having an upper end drum 19 and a lower end drum 20.

The magnetic core 13 of the transformer 12 may be constructed in the usual manner of a plurality of stacked laminations. In the form illustrated, the magnetic core is of the shell type having a primary winding 14 and a secondary winding 15 mounted upon the central leg thereof. Positioned between the primary winding and the secondary winding are two magnetic shunts 16 which magnetically bridge the space between the central magnetic leg and each of the outer magnetic legs. The purpose of the magnetic shunt 16 is to limit the value of the secondary current by by-passing a portion of the primary flux when the secondary current increases beyond a pre-determined safe limit. The reluctance of the magnetic shunts is greater than the reluctance of the secondary core portion surrounded by the secondary winding. Therefore,

when the secondary current is relatively low, substantially all of the primary flux interlaces the secondary winding. However, when the secondary current becomes relatively high, there is 5 a large opposing secondary flux set up in the secondary core portion to oppose the passage of the primary flux. Under this condition, a portion of the primary flux is by-passed through the shunts 16 with the result that the secondary current is decreased to its safe operating value.

In accordance with the usual construction of 10 transformers, the magnetic core 13 and the primary winding 14 and the secondary winding 15 may be suitably supported within the housing 18 and properly insulated from the housing 18 by an insulating compound which is poured in a molten condition in the transformer housing 18. In order to contain the insulating compound, the transformer housing 18 is provided with a lower partition 22 and an upper partition 21. The lower partition 22 snugly fits within the housing 18 and may be fastened thereto by any suitable means, such as, by welding which is indicated by the reference character 27. During the construction 15 of the transformer, the molten insulating compound is poured in from the top after which the upper partition 21 is snugly pressed into the upper open end of the housing 18.

In order to suspend the entire combined transformer and illuminating device in a good strong 20 manner, I employ an upper bracket 37 which has its lower ends connected to the upper inside edge of the housing 18 by any suitable manner, such as by welding which is indicated by the reference character 38. The upper end of the bracket 37 is provided with an opening into which a threaded collar 39 is mounted. As illustrated, the collar 39 is provided with a stepped shoulder 40 so as to engage the underneath side of the bracket 37 25 and make a good strong support for suspending the combined transformer and illuminating device. The threaded collar 39 is provided with suitable female threads to receive the male threads of the conduit 41 from which the entire 30 combined transformer and illuminating device may be suspended. In order to facilitate the wiring of the transformer, the upper end drum 19 is provided at its upper end with an opening 42. Therefore, when making the electrical connections, the upper end drum 19 may be disconnected 35 by means of the screws 43 from the upper end of the housing 18 and slid up the conduit 41 to provide access for connecting the internal wiring connections to the switch 78 mounted on the inside wall of the housing 18 and to the insulated 40 and independent terminals 28, 29, 30, 31, and 32 mounted upon the upper partition 21. In the position shown, the supply conductor 71 is connected to the insulated terminal 28 and the supply 45 conductor 72 is connected to the upper terminal of the switch 78. The lower terminal of the switch 78 may be connected by a conductor 77 to either the insulated terminals 29, 30, or 31. In the position shown it is connected to the terminal 30. The underneath side of the terminal 28 is connected by a conductor 73 to the lower 50 end of the primary winding 14. The underneath side of the terminals 29, 30, and 31 are respectively connected by means of the conductors 74, 75, and 76 to the upper, the middle, and the lower 55 taps of the primary winding, which taps are indicated generally by the reference character 17. Therefore, by connecting the conductor 77 to either the terminals 29, 30, or 31, we obtain a

different impressed voltage upon the primary winding 14.

The illuminating device 11 comprises a gaseous tube 59, two incandescent lamps 62 and 65, and a reflector 54 having suitable ventilating openings 66. The gaseous tube may be of any suitable type, such, for example, as a high pressure mercury vapor tube or any other tube operated by the ionization of the contained gas. In the operation of these gaseous tubes, it requires a high initial voltage to cause ionization, but when ionization is once established, the normal operating voltage is relatively low. The socket 57 for the gaseous tube and the sockets 60 and 64 for the incandescent lamps 62 and 65 may be suitably mounted upon a supporting plate 55. For instance, the socket 57 for the gaseous tube may be connected to the supporting plate 55 by the screws 58, the socket 60 for the incandescent lamp 62 may be connected to the supporting plate 55 by the screws 61, and the socket 63 for the incandescent lamp 65 may be connected to the supporting plate 55 by the screws 64. The supporting plate 55 is in turn connected to a supporting flange 52 by means of the threaded cap screws 56. As illustrated, the supporting flange 52 is threadably connected by means of the thread 53 to a threaded collar 49, which is supported by a bracket 47 having its upper ends connected to the lower inside edge of the housing 18 of the electrical energizing device 10. The upper ends of the lower bracket 47 may be connected to the housing in any suitable manner such as by welding, which is indicated by the reference character 48. The threaded collar 49 is provided with a stepped shoulder 50 for engaging the lower bracket 47 to make a good strong connection for supporting the weight of the electrical illuminating device 11. By means of the foregoing construction, the illuminating device 11 may be threadably attached or detached from the electrical energizing device 10. Before threadably attaching the illuminating device 11 to the electrical energizing device 10, the lower end drum 20 may be attached to the housing of the electrical energizing device 10 by means of the screws 51.

The incandescent lamps 62 and 65 are energized by the supply voltage. The circuit for illuminating the incandescent lamp 62 may be traced as follows: Beginning with the supply conductor 71, current flows through the terminal 28, a conductor 81, a terminal 33 insulatably mounted in the lower partition 22, a conductor 86 to the socket 60, whereupon the current flows through the incandescent lamp 62, and back through the socket to a conductor 98 which is connected to the terminal 36 insulatably mounted in the lower partition 22, from whence current flows through the conductor 86, the terminal 32 in the upper partition 21, a conductor 79 to the switch 78 and finally to the other supply conductor 72. The incandescent lamp 65 is energized by two conductors 85 and 88 which are respectively connected to the terminals 33 and 36. The gaseous tube 59 is energized by two conductors 87 and 88 which are respectively connected to the terminals 34 and 35, which in turn are connected to the secondary winding 15 of the transformer by means of the conductors 83 and 84. Therefore, when the switch 78 is turned on, the gaseous tube 59 is energized by the transformer and the two incandescent lamps 62 and 65 are energized directly from the supply source. As previously explained, the transformer, by reason of the magnetic shunts 16, is adapted to give a high initial

voltage to ionize the gas in the gaseous tube 59 and adapted, when the gas is once ionized, to reduce the value of the secondary voltage to such value as to limit the value of the secondary current flowing through the gaseous tube.

In Figure 3, I show a modified arrangement of my embodiment of the combined transformer and illuminating device and like reference characters represent like parts to those shown in Figures 1 and 2. In this embodiment of my invention, I utilize a capacitor 100 which is connected in circuit relation with the transformer to improve the power factor of the lighting circuit. As illustrated, the housing 95 is provided with a transformer 94 and the capacitor 100. Separating the capacitor 100 and the transformer 94 is a central partition 97 having suitable terminals to take care of the proper electrical connections.

The primary winding 96 of the transformer is provided with a plurality of taps. The tap which is illustrated on the left hand side of the primary winding and intermediate of its two ends is connected by a conductor 104 through a terminal in the middle partition 97 to a conductor 103, which is in turn connected to the terminal 28 in the upper partition 21 and which is energized by the supply conductor 71. The lower terminal on the right hand side of the primary winding 96 is connected to the upper terminal 101 of the capacitor 100 by means of a conductor 98 which leads to the third terminal from the left in the central partition and which third terminal is in turn connected to the upper terminal 101 of the capacitor 100. The upper terminal on the right hand side of the primary winding 96 is connected to the terminal 102 of the capacitor 100 by means of a conductor 106 which is connected to the fifth terminal from the left in the central partition, which fifth terminal is in turn connected to the terminal 102 of the capacitor 100. The terminal 102 of the capacitor is also connected to the terminal 29 which is energized by the supply conductor 72 through the switch 78. The second tap from the top on the right hand side of the primary winding 96 is connected by means of a conductor 107 to the fourth terminal from the left in the central partition 97, which fourth terminal is in turn connected to the terminal 30 in the upper partition 21. The third terminal from the top on the right hand side of the primary winding 96 is connected by means of a conductor 108 to the second terminal from the left in the middle partition 97 which second terminal is connected to the terminal 31 in the upper partition 21. Therefore, by the arrangement of the foregoing connections, the capacitor 100 is connected across the entire primary winding 96 to improve the power factor of the lighting circuit. Also by arrangement of the adjustable taps, the transformer may be connected to the supply circuits having different voltages and yet give substantially the same primary flux to obtain uniform operations for the gaseous tube. The circuit connections between the secondary winding of the transformer 94 and the gaseous tube are the same as that previously described with reference to Figures 1 and 2. The lower terminals 33 and 36 which take care of energizing the incandescent lamps are respectively connected to the upper terminals 28 and 32 in the upper partition 21. The terminal 33 is connected to the upper terminal 28 by means of the two conductors 105 and 103 and the lower terminal 36 is connected to the upper terminal 32 by means of the conductors

110 and 109. The operation of the embodiment shown in Figure 3 is substantially the same as that described with reference to Figures 1 and 2 with the added provision, however, that the capacitor 100 improves the power factor of the circuit for energizing the gaseous tube 59.

In Figure 4, I show a further modified form of my invention in that the socket 114 for the gaseous tube 118 is mounted inside of the end drum 20 of the transformer housing 18. The socket 114 is connected by means of screws 115 to a flanged support 112 which threadably engages a collar 113 that is carried by a transverse bracket 111 having its ends suitably connected as by welding to the lower bracket 47. The reflector 15 20 116 may be connected to the lower bracket 47 by means of screws 117. In this embodiment of the invention, the transformer is substantially the same as those shown in Figures 1, 2, and 3 and may be utilized with or without a capacitor.

In Figure 5, I show a somewhat different arrangement of suspending the electrical energizing device 10 and the electrical illuminating device 11. In this embodiment, the electrical illuminating device 11 is suspended by means of a conduit 130 25 that is carried from a collar 122 mounted directly upon the lower end drum 120 which is connected to the housing 18 by means of the screws 128. The upper end of the housing 18 is carried directly by the upper end drum 119 which is connected 30 to the housing 18 by the screws 128. In this construction, the weight is carried solely by the end drums 119 and 120 without the utilization of brackets as shown in the other forms of my invention. The upper end of the drum 119 is provided with a threadable collar 121 which threadably engages the conduit 123. The electrical connections between the transformer and the supply conductors 125 and 126 are made in a conduit box 124 which is suspended by a conduit 127. 40 In this form of my invention the transformer and the internal wiring connections are the same as those shown in Figures 1, 2, and 3, and the transformer may be with or without a capacitor, and the electrical illuminating device 11 may be 45 provided either with a single gaseous tube as shown in Figure 4 or with a gaseous tube and a plurality of incandescent lamps as shown in Figures 1 and 2.

In Figure 6, I show a reactance coil 131 which 50 may, under certain operating conditions, be utilized instead of the transformers shown in the other views of the drawings. As illustrated, the winding 132 of the reactance 131 is connected in series with the supply conductors 133 and 134 and the gaseous tube 135. As illustrated, the winding 132 is provided with additional taps 137 and 138 which may be connected to the supply conductor 133 to vary the voltage. The reactance 131 may 55 be mounted in the housing in the same manner as the transformers are mounted in the housings shown and described with reference to Figures 1, 2, 3, 4, and 5.

Although I have described my invention with a 60 certain degree of particularity, it is understood that the present disclosure has been made only by way of example and that numerous changes in the details of construction and the combination and arrangement of parts may be resorted to 65 without departing from the spirit and the scope of the invention as hereinafter claimed.

I claim as my invention:

1. The combination, with an electrical illuminating device, of an electrical device for energiz- 75

ing the illuminating device, a housing for the electrical energizing device, said housing having a central portion and two end portions, a first partition for separating the central portion and 5 one of said end portions, a second partition for separating the central portion and the other of said end portions, means for mounting the electrical energizing device between the two partitions, means for supporting the electrical illuminating device from one of said end portions, means for suspending the electrical illuminating device and the electrical energizing device as a unit from the other of said end portions, terminal members carried by the first partition, supply 10 conductors passing through the suspending means and connected to the terminals mounted on the first partition, tap conductors interconnecting the electrical energizing device and the terminals mounted on the first partition, and 15 circuit connections passing through the second partition and the supporting means for interconnecting the electrical energizing device and the illuminating device.

2. The combination, with an electrical illuminating device, of an electrical device for energizing the illuminating device, a housing for the electrical energizing device, said housing having a central portion and two end portions, a first partition for separating the central portion and 10 one of said end portions, a second partition for separating the central portion and the other of said end portions, means for mounting the electrical energizing device between the two partitions, means for supporting the electrical illuminating device from one of said end portions, means for suspending the electrical illuminating device and the electrical energizing device as a unit from the other of said end portions, circuit 15 connections passing through the suspending means and the first partition to energize the electrical energizing device, means mounted on the first partition for adjustably varying the said circuit connections, and circuit connections passing through the second partition and the 20 supporting means for interconnecting the electrical energizing device and the illuminating device.

3. The combination, with an electrical illuminating device having a gaseous tube and an 25 incandescent lamp, of an electrical device for energizing the gaseous tube, a housing for the electrical device, said housing having a central portion and two end portions, a first partition for separating the central portion and one of 30 said end portions, a second partition for separating the central portion and the other of said end portions, means for mounting the electrical energizing device between the two partitions, means for supporting the electrical illuminating 35 device from one of said end portions, means for suspending the electrical illuminating device and the electrical energizing device as a unit from the other of said end portions, circuit connections passing through the suspending means and the 40 first partition to energize the electrical energizing device, means mounted on the first partition for adjustably varying the said circuit connections, circuit connections passing through the second partition and the supporting means for 45 interconnecting the electrical energizing device and the gaseous tube, and circuit connections passing through the two partitions and the supporting device for energizing the incandescent lamp.

75 4. An electrical suspension device arranged to

be suspended at its upper end from a supply conduit and adapted to carry an electrical illuminating device from its lower end comprising, in combination, an electrical device arranged to be energized by supply conductors passing through 5 the supply conduit and adapted to deliver current to the electrical illuminating device, a housing for the electrical device, upper bracket means mounted inside of the housing for suspending the electrical device, the housing and the 10 illuminating device, the said upper bracket means having connection means for detachably connecting the said bracket to the supply conduit, lower bracket means mounted inside of the housing from which the illuminating device may be suspended, the said lower bracket means having connection means to which the illuminating device may be detachably suspended, the upper end of the housing having an opening through which the lower end of the supply conduit may 15 pass and engage the connection means of the upper bracket, the lower end of the housing having an opening registering with the connection means of the lower bracket means, the said electrical device having conductor leads arranged for 20 electrical connections inside of the housing with the supply conductors, the said housing having a removable portion for giving access to the inside of the housing for making said electrical connections.

5. An electrical suspension device arranged to be suspended at its upper end from a supply conduit and adapted to carry an electrical illuminating device from its lower end comprising, in combination, an electrical device arranged to be energized by supply conductors passing through 25 the supply conduit and adapted to deliver current to the electrical illuminating device, a housing for the electrical device, upper bracket means mounted inside of the housing for suspending the electrical device, the housing and the illuminating device, the said upper bracket means having connection means for detachably connecting the said bracket to the supply conduit, lower bracket means mounted inside of the housing from which the illuminating device may be suspended, the said lower bracket means having connection means to which the illuminating device may be 30 detachably suspended, said housing having a central portion and an upper and a lower end portion, said central portion encompassing the electrical device and the upper and lower end portions covering respectively the upper and lower bracket means, the upper end portion of the housing having an opening through which the lower end of the supply conduit may pass and engage the connection means of the upper bracket, the lower end portion of the housing having an opening registering with the connection means of the lower bracket means, the said 35 electrical device having conductor leads arranged for electrical connections inside of the housing with the supply conductors, the said housing having a removable portion for giving access to the inside of the housing for making said electrical connections.

6. An electrical suspension device arranged to be suspended at its upper end from a supply conduit and adapted to carry an electrical illuminating device from its lower end comprising, in 40 combination, an electrical device arranged to be energized by supply conductors passing through the supply conduit and adapted to deliver current to the electrical illuminating device, a housing for the electrical device, upper bracket means 45

5 mounted inside of the housing for suspending the electrical device, the housing and the illuminating device, the said upper bracket means having connection means for detachably connecting the said bracket to the supply conduit, lower bracket means mounted inside of the housing from which the illuminating device may be suspended, the said lower bracket means having connection means to which the illuminating device 10 may be detachably suspended, the upper end of the housing having an opening through which the lower end of the supply conduit may pass and engage the connection means of the upper bracket, the lower end of the housing having an opening registering with the connection means of the lower bracket means, terminal members positioned in the housing and arranged for electrical connection with the supply conductors, the said electrical device having conductor leads arranged for electrical connections with the terminal members inside of the housing, the said housing having a removable portion for giving access to the inside of the housing for making said electrical connections between the terminal members and the supply conductors.

7. An electrical suspension device arranged to be suspended at its upper end from a supply conduit and adapted to carry an electrical illuminating device from its lower end comprising, 20 in combination, an electrical device arranged to be energized by supply conductors passing through the supply conduit and adapted to deliver to the electrical illuminating device, a housing for the electrical device, upper bracket means mounted inside of the housing for suspending the electrical device, the housing and the illuminating device, the said upper bracket means having connection means for detachably connecting the said bracket to the supply conduit, lower bracket means mounted inside of the housing from which the illuminating device may be suspended, the said lower bracket means having socket means to which the illuminating device may be detachably suspended, said housing having a central portion and an upper and a lower end portion, said central portion encompassing the electrical device and the upper and lower end portions covering respectively the upper and lower bracket means, the upper end portion of the housing having an opening through which the lower end of the supply conduit may pass and engage the connection means of the upper bracket, the lower end portion of the housing having an opening registering with the socket means of the lower bracket means, the said elec-

trical device having conductor leads arranged for electrical connections inside of the housing with the supply conductors, the said housing having a removable portion for giving access to the inside of the housing for making said electrical connections. 5

8. A device arranged for use with an electrical illuminating device and a supply conduit having supply conductors comprising, in combination, a transformer for energizing the illuminating device, a first housing provided on one side of the transformer, a second housing provided on the other side of the transformer, means for mounting the transformer between the two housings and providing a unitary structure, said second 10 housing having connection means to which the illuminating device may be attached, said first housing having connection means for the supply conduit, terminal members provided in the first housing and arranged for connection with the supply conductors, said transformer having tap conductors connected to the terminal members, said first housing having a removable portion for giving access to the inside thereof for making electrical connections between the supply 15 conductors and the terminal members. 20

9. A device arranged for use with an electrical illuminating device and a supply conduit having supply conductors, said illuminating device including a gaseous tube and an incandescent lamp, 25 comprising, in combination, a transformer for energizing the gaseous tube of the illuminating device, a first housing provided on one side of the transformer, a second housing provided on the other side of the transformer, means for mounting the transformer between the two housings and providing a unitary structure, said second housing having connection means to which the illuminating device may be attached, said first housing having connection means for the supply conduit, terminal members provided in the first housing and arranged for connection with the supply conductors, said transformer having tap conductors connected to the terminal members, said first housing having a removable portion for giving access to the inside thereof for making electrical connections between the supply conductors and the terminal members, and conductor means for energizing the incandescent lamp, said conductor means being energized 35 by the supply conductors and extending from the first housing to the second housing and arranged for connection with the incandescent lamp. 40 45 50 55

JAMES A. COMSTOCK. 55
